UNITED STATES PATENT OFFICE.

THOMAS S. SHIBE, OF PHILADELPHIA, PENNSYLVANIA

METHOD OF PREPARING BASEBALL CENTERS.

Original application filed July 19, 1924, Serial No. 727,010. Divided and this application filed September 13, 1924. Serial No. 737,569.

To all whom it may concern:

Be it known that I, THOMAS S. SHIBE, a citizen of the United States, and resident of Philadelphia, in the county of Philadelphia and State of Pennsylvania, have invented certain new and useful Improvements in Methods of Preparing Baseball Centers, of which the following is a specification.

My present invention relates to improvements in base balls of the type having a cork center surrounded by a layer of rubber, such as is shown, for example in Letters Patent of the United States, No. 932,911, dated August 31, 1909, and in the art of making the same, and is a division of my co-pending application Serial No. 727,010.

The invention aims to provide a ball of this character having a cork center provided with a homogeneous rubber shell in which the center is accurately centered or positioned.

The invention further aims to provide a ball having a cork center provided with a rubber enclosing shell of such construction that it can be vulcanized on the center without danger of burning or destroying the latter.

A further object is to avoid having any air trapped between the sheath and the cork center.

With these various objects in view, the invention includes the novel method herein-after described, and particularly defined by the appended claims.

In order that the invention may be better understood, reference is made to the accompanying drawing, in which:

Figure 1 is a sectional view of a complete ball, and

Fig. 2 is a detail view partly in section and partly in elevation, showing the cork center and enclosing shell.

Fig. 3 is a sectional view of a mold used in carrying out the process.

Referring by reference characters to this drawing, the numeral 1 designates a cork sphere designed to form the inner core or center of the ball, and 2 an enclosing sheath or shell of relatively firm and highly resili-ent rubber which is of homogeneous forma-tion, being vulcanized around and completely enveloping the cork center.

In providing the cork center with a ho-

mogeneous vulcanized enclos ng shell, I have 55 found that unless venting means are pro-vided, there is liability of air being trapped between the cork center and shell which makes the ball erratic in bounding, this trapping of air being rendered more likely 60 by reason of the cellular structure of the cork. Furthermore, the entrapped air is expanded during the vulcanizing action and tends to produce distortion, and it has fur-thermore been found difficult to provide a 65 center with a homogeneous shell in which the cork is accurately centered; or in other words, is surrounded by a layer or shell of rubber of uniform thickness. To avoid these various objections, I provide the shell 70 with a plurality of vent passages. These are preferably in the form of cylindrical openings or passages 3, through the wall of the shell from the inner surface to the outer periphery. They are preferably distributed 75 evenly throughout the entire circumference of the shell, as shown, and may be left open as shown, in which case they constitute en-closed chambers or cells in the finished ball, as shown in Fig. 1, or they may be filled 80 with a fibrous material which will permit the passage of air. In the formation of my improved center, the rubber shell is prefer-ably formed in two hemispherical sections by the use of molds such as shown for ex-85 ample, in Fig. 3, comprising male and fe-male members 4 and 5, which when fitted to-gether, provide an enclosed cavity 2^a of hemispherical shape. The rubber com-pound is placed in this cavity and subjected 90 to partial vulcanization, the cure being car-ried only to such a point as to enable the rubber compound to maintain its proper shape while being subsequently manipulated 95 and treated. After two such shells are made 95 they are placed together to form the com-plete sphere shown in Fig. 2, with the cork center enclosed there-between, the whole then being placed in a ball vulcanizing mold 100 of the customary form and subjected to heat to complete the cure, whereupon the edges of the two hemispherical shells are vulcan-ized together to form a homogeneous shell. The vents in the wall of the shell may be 105 formed by providing any suitable cores or filling members during vulcanization. The form of mold shown in Fig. 3 affords a very satisfactory means of supplying these vent

openings or passages, though it will be readily understood that many other forms or ways of accomplishing this are available. In the mold shown in Fig. 3, one of the 5 members, as for instance the female member 5, may be provided with a polar projection 5^a which would form one of the passages in the shell, and the member 4 could be provided with a plurality of circumferentially spaced semi-circular projections 4^a which would form spaced semi-circular recesses in the edge of the shell, and when two half shells were brought together with these 10 recesses in alignment, cylindrical openings or 15 passages would be the result. Other and intermediate passages would be provided by the use of removable core pins 5^b.

If desired, during final vulcanization in the ball mold, the openings in the shell could 20 be filled with core pins. This would not interfere with the venting of the air, as it could pass out around the pins, or they could be made tubular so that air would pass 25 through them, or could be of a porous nature. The air which had passed out through the vents would, of course, escape from the mold by the usual parting line of the mold.

Having thus described my invention, what I claim is:

1. The herein-described method of making 30 a core or center for base balls, which consists in forming a pair of partially cured hemispherical sections of rubber compound, assembling said sections in the form of a sphere with a spherical cork center of filling material therein, and subsequently completing the core and vulcanizing the edges of said shell sections together while venting the space within the shell.

2. The herein-described method of making 40 a core or center for base balls, which consists of forming a pair of partially cured hemispherical sections of rubber compound, provided with a plurality of passages 45 through the walls thereof, assembling said sections with their edges in contact, and with an enclosed cork center, and subsequently completing the vulcanization to join said edges together and form a homogeneous shell.

In testimony whereof, I affix my signature.

THOMAS S. SHIBE.
